T. J. MILLS AND E. T. MORRIS.
PRINTING MACHINE FOLDING CYLINDER.
APPLICATION FILED NOV. 13, 1919.

1,365,933.

Patented Jan. 18, 1921.

UNITED STATES PATENT OFFICE.

THOMAS JOSEPH MILLS AND EDWARD THOMAS MORRIS, OF LONDON, ENGLAND,
ASSIGNORS TO R. HOE AND CO., OF NEW YORK, N. Y., A CORPORATION OF NEW
YORK.

PRINTING-MACHINE FOLDING-CYLINDER.

1,365,933.

Specification of Letters Patent. Patented Jan. 18, 1921.

Application filed November 13, 1919. Serial No. 337,806.

To all whom it may concern:

Be it known that we, THOMAS JOSEPH MILLS and EDWARD THOMAS MORRIS, both subjects of the King of Great Britain, residing at 109 Borough road, London, England, have invented new and useful Improvements in Printing-Machine Folding-Cylinders, of which the following is a specification.

This invention relates to improvements in 10 folding cylinders used in rotary printing machines, and in the mechanism for actuating the pin holders carried thereon.

The object of this invention is to provide 15 a folding cylinder giving easy and safe access to the pin holders and the cranks for actuating them during the operation of adjustment or renewal, while at the same time the cylinder is of greater strength than hitherto.

20 In the case of a folding cylinder as usually constructed, in which the cylinder consists of an outside shell carried by a few spokes or bosses, there is considerable shock and vibration when the gutter bar in the 25 folding cylinder is co-acting with the knife in the cutting cylinder, and in a folding cylinder so constructed the rod carrying the cranks for actuating the pin holders has been situated inside the shell of the cylinder.

30 This arrangement possesses the following disadvantages:—

(1) If the operator wishes to adjust or renew a pin holder he can only do so either through the end of the cylinder or through 35 the slots provided for the folding blades.

(2) In the above positions he cannot see what he is doing and has to rely mainly on the sense of touch.

(3) There is always the danger of the 40 machine being accidentally started with serious results to the operator.

According to our invention we provide a longitudinal rib connecting the gutter bar to the central tube of the folding cylinder 45 so that the load of impact between the folding and cutting cylinders is distributed along the whole length of the central tube, instead of at several points as hitherto, and we provide in the folding cylinder a trough 50 shaped recess in which are situated the rod and cranks for actuating the pin holders. Preferably the recess extends across almost the whole of the cylinder, one wall of the trough being formed by the longitudinal rib 55 above mentioned and the recess is of a suffi-

cient size to afford ready accessibility and to allow of the withdrawal of a pin holder when disengaged from its crank pin.

The bearings for the rod are preferably situated at each end of the recess and there 60 may be an additional bearing in the middle.

In order to be able more readily to replace the pin holder, each holder is actuated by a crank pin carried by a double crank, one crank being permanently secured to the 65 actuating rod while the other is detachably fixed in position by means of a set screw, the crank pin being fixed to the detachable crank and slideable in the fixed crank, or vice versa. In order to receive a pin holder 70 it is only necessary to slacken the set screw holding the detachable crank and to slide it along the actuating rod, when the pin holder can be withdrawn and a new one inserted.

In the accompanying drawings which 75 illustrate the invention, Figure 1 is a front view, Fig. 2 a part section on the line A—A, Fig. 1, and a part end elevation; Figs. 3 and 4 are a side and end elevation respectively to a larger scale of the crank mechanism for 80 actuating the pin holders.

1 is the folding cylinder of a rotary printing machine, 2 are longitudinal ribs extending across the cylinder and connecting the gutter bars 3 to the central tube 4 of 85 the cylinder 1. 5 are trough shaped recesses extending across almost the whole of the cylinder 1, one wall of the recesses being formed by the longitudinal ribs 2; situated within the recesses 5 are the crank rods 90 6 and cranks for actuating the pin holders 7. Each pin holder 7 is actuated by a crank pin 8 carried by a double crank consisting of a crank 9 permanently secured to the rod 6 by a set screw 10 and a crank 11 detachably fixed in position by a set screw 12. The crank pin 8 is fixed to the detachable crank 11 and is slideable in the permanent crank 9. The crank pin 8 may, if desired, be fixed to the permanent crank 9 and slideable 95 in the detachable crank 11.

In order to remove a pin holder 7 it is only necessary to slacken the set screw 12 holding the detachable crank 11 and to slide it together with its crank pin 8 along the 105 actuating rod 6 when the pin holder 7 can be withdrawn and a new one inserted.

What we claim is:—

1. In a rotary printing machine, a folding cylinder having in it a longitudinal 110

recess, an actuating rod situated within the recess, a crank mounted on the rod, a crank pin on said crank, and a pin holder adapted to be actuated by said crank and be withdrawn bodily into the longitudinal recess when disengaged from its crank pin.

5. In a rotary printing machine, an actuating rod, a crank permanently fixed to the rod, a second crank detachably secured to 10 and slidable on the rod, and a crank pin carried by one of the cranks.

15. In a rotary printing machine, a folding cylinder having in it a longitudinal recess, an actuating rod, situated within the recess, a crank permanently fixed to the rod, a second crank detachably secured to and slidable on the rod, and a crank pin carried by one of the cranks.

20. In a rotary printing machine, a folding cylinder having in it a longitudinal recess, a gutter bar, a central tube, a longitudinal rib connecting the gutter bar and central tube, an actuating rod situated within the recess, a crank mounted on the rod, a 25 crank pin on said crank, and a pin holder adapted to be actuated by said crank.

25. In a rotary printing machine, a folding cylinder, a longitudinal recess therein, a gutter bar, a central hub, a longitudinal rib connecting the gutter bar and central hub, an actuating rod in the recess, a member 30 permanently secured to the rod for operating it, a member detachably secured to

and slidable on the rod, and an operating pin carried by one of said members. 35

6. In a rotary printing machine, a folding cylinder, having in it a longitudinal recess, an actuating rod situated within the recess, a gutter bar, a central tube, a longitudinal rib connecting the gutter bar and 40 central tube, a crank permanently fixed to the rod, a second crank detachably secured to and slidable on the rod, and a crank pin carried by one of the cranks.

7. In a rotary printing machine, an actuating rod, a member for actuating the rod permanently fixed thereto, a member detachably secured to and slidable along the rod, an operating connection carried by one of the members, and a pin holder operated by 45 the connection and removable therefrom when the detachable member has been moved along the rod.

8. In a rotary printing machine, a folding cylinder having a longitudinal recess 55 accessible from the outer side of the cylinder, a pin holder extending into the recess, and means in the recess for actuating the holder, said holder being bodily movable from the side of the cylinder into the longitudinal recess. 60

In testimony that we claim the foregoing as our invention we have signed our names this 27th day of October, 1919.

THOMAS JOSEPH MILLS.
EDWARD THOMAS MORRIS.
